UNITED STATES PATENT OFFICE

VIRGINIA D. AYRES, OF BERLIN, MARYLAND

DESIGN FOR A RAG DOLL

Application filed February 6, 1930. Serial No. 34,437. Term of patent 3½ years.

To all whom it may concern:

Be it known that I, VIRGINIA D. AYRES, a citizen of the United States, residing at Berlin, in the county of Worcester and State of Maryland, have invented a new, original, and ornamental Design for Rag Doll, of which the following is a specification, reference being had to the accompanying drawing, forming part thereof.

Fig. 2 is a side elevation.

I claim:

The ornamental design for a rag doll as shown.

VIRGINIA D. AYRES.
